CLAIM

The ornamental design for a dog chew, as shown and described.

DESCRIPTION

FIG. 1 is a rear-top-right side perspective view of a dog chew, showing the design;

FIG. 2 is a front elevation view of the dog chew of FIG. 1, showing the design;

FIG. 3 is a right side elevation view of the dog chew of FIG. 1, showing the design;

FIG. 4 is a left side elevation view of the dog chew of FIG. 1, showing the design;

FIG. 5 is a top plan view of the dog chew of FIG. 1, showing the design;

FIG. 6 is a bottom plan view of the dog chew of FIG. 1, showing the design;

FIG. 7 is a rear elevation view of the dog chew of FIG. 1, showing the design; and,

FIG. 8 is a cross-sectional view of the dog chew of FIG. 1 along line 8-8, showing the design.

The broken lines shown in the drawings depict portions of the dog chew that form no part of the claimed design.

1 Claim, 8 Drawing Sheets
